United States Patent Office.

DAVID B. MOSHER AND CHARLES C. MOSHER, OF SENECA FALLS, NEW YORK.

Letters Patent No. 76,799, dated April 14, 1868.

IMPROVED WINDOW-BLIND FASTENER.

The Schedule referred to in these Letters Patent and making part of the same.

TO ALL WHOM IT MAY CONCERN:

Be it known that we, DAVID B. MOSHER and CHARLES C. MOSHER, of Seneca Falls, in the county of Seneca, and State of New York, have invented a new and useful Improvement in Window-Blind Operators; and we do hereby declare that the following is a full, clear, and exact description of the construction and operation of the same, reference being had to the annexed drawings, making a part of this specification, in which—

Figure 1 is a perspective view of the window-frame and blind, with the fixtures attached.

Figures 2, 3, 4, 5, 6, and 7 are views of the different parts

The letters of reference refer to the same parts in each.

Letters A A is a perspective view of the window with the blind partly open. B B is a shaft running through the window-casing, with a bevel-gear on the outside. C C is a bevel-gear with an arm attached, and is connected with gear and shaft B B, and is operated by the knob or handle H H, from the inside of the building, without raising the window. E E is a link, fast to the blind, A, for the arm C C to work in. D D D is a box or frame inserted in the outside of window-frame for the gears to work in. F F is a dog for stopping the blind and holding it at any desired point. G G is a rose made in two parts to connect the knob or handle H H and shaft B B together.

Having thus described our invention, we claim—

The combination of the shaft and gear B, gear, with arm attached, C, box or frame D, link E, dog F, rose G, knob or handle H, when made substantially as specified, and applied as herein set forth.

DAVID B. MOSHER,
CHARLES C. MOSHER.
